BULK STORAGE SYSTEM

William D. Coe and Howard S. Murray, Milton-Freewater, Oreg.; said Murray assignor to said Coe

Filed July 1, 1957, Ser. No. 669,158

2 Claims. (Cl. 21—109)

This invention relates generally to the storage and treatment in storage of dry cereal grains and grass seeds and more particularly to a bulk storage system for such materials.

It is well known that in the prior art of storage, cleaning, fumigating, and like treatment of these materials, it has been necessary to provide large stationary hopper bottom bins capable of holding large quantities of the materials and therefor permanently placed. To move such material from one storage location to another requires that the loose material be taken from one large bin in a loose condition, loaded in a bin type conveyance of some type and then unloaded in a loose condition at a newly desired location. Again, when it was desired to clean such material, a similar procedure was used to transport the grain or seed to a cleaning plant where it was cleaned, sacked and, if desired, fumigated in an air tight chamber while in the sacked condition. These prior art methods required large money outlays in permanent installations and much time and labor expense in handling.

It is the primary object of this invention to provide means for reducing the fixed capital required for the provision of facilities for the bulk storage of grain and to reduce the cost of time and labor involved in handling, treating and storing the grain.

It is a second object to provide a plurality of standardized metal boxes or cells which may be handled conveniently by a modern type of lift truck, which cells can be stored in multiples on any flat hard surface and which can be transported on any flat conveying surface.

It is a third object to provide such cells each of which has a completely open top and to provide a simple top cover which can be stored, stacked or handled conveniently in multiples thereof but which are individually light in weight and easy for one man to apply to an individual cell.

It is a fourth object to provide such a cell formed of metal plate and shapes in simple form requiring a minimum of material.

It is a fifth object to provide such a cell generally rectangular in over all plan and side elevation, one side of the cell having a hole formed therethrough near its upper edge with cover means for the hole rotatably secured to the side for rotation between two positions of cover for the hole with uncover positions between the two cover positions.

It is a sixth object to provide such a cell with a hole through an upper side wall and means for alternately covering said hole with a vermin proof breather screen

2

or a rubber grommet through which a fumigation needle may be inserted to the inside of the cell.

It is a seventh object to provide such cells which can be stored in rectangular blocks of any desired length, two cells wide and any practical height thus leaving the hole in each cell for breathing or fumigation accessible on the outside of the two cell wide stack.

It is an eighth object to provide such cells with laterally spaced supporting means on the bottoms thereof to provide sufficient separation of the cells in vertical stacks for placing the supporting forks of a lift truck and for maintaining the bottom cell of the stack off the supporting ground or other supporting surface.

It is a ninth object to provide a fountain needle for penetrating the rubber grommet cover of the hole in the side of such a cell for the purpose of injecting a fumigating fluid into the cell.

It is a tenth object to provide such a needle with a storage chamber for fluid under pressure, an intermediate measuring chamber for doses of such fluid and means for alternately opening said measuring chamber to the storage chamber and to the needle.

How these and other objects are attained are explained in the following description referring to the attached drawings in which

Fig. 1 shows a storage yard of this system in which spaced blocks of laterally, longitudinally and vertically closely spaced cells are tiered.

Fig. 2 shows an enlarged side view of the fragment 2 of one of the cell blocks of Fig. 1.

Fig. 3 shows a sectional view along the line 3—3 of Fig. 2.

Fig. 4 is a view in side elevation of the novel fountain needle used for fumigation of the material stored in accordance with the system of this invention.

Like numerals of reference refer to like parts in the several figures of the drawings.

Referring now to the drawings, in Fig. 1 is shown a storage yard in accordance with the present system in which a hard flat platform having any suitable surface like concrete, black top, wood or well drained and rammed earth supports multiples of the cells of this invention tiered as shown in blocks two cells wide, four cells high, and of any desired length but preferably not over 25 cells long. Since the cells individually are preferably cubes of four foot overall dimensions the preferred block of cells would be 8 ft. wide, 16 ft. high and 100 ft. long. The width limitation is fixed by the requirement that each cell must face on an aisle. The height limitation is not fixed but is a practical limitation for the use of commonly available lift trucks. The length limitation is not fixed but it is found that fifty feet is a good limit for a lift truck to work into an aisle of minimum width. The aisle width should be about 12 feet to give working space for the lift truck.

Fig. 2 shows an enlarged side view of the fragment 2 taken from the nearest cell block shown in Fig. 1. In Fig. 2 are shown a front elevation of cell 12 and fragments of cells 11 and 13 with the cells stacked as shown in Fig. 1.

As shown for cell 12 in Fig. 2, each of the cells is in the form of a hollow rectangular truncated pyramid open at the top and formed of about 16 gage steel sheets. The cell is reinforced around the top with a metal angle 14 about 3 inch by 3 inch in size and welded to the side

sheets. Welded to the underside of the bottom sheet 15 of the cell in laterally spaced parallel relation are three U-shaped supporting skids 16. These details are not shown in the schematic yard drawing of Fig. 1.

Between each of the vertically stacked cells is a cover 17 made of any suitable material of which hardboard such as "Masonite" three sixteenth inches thick has been found satisfactory. Such covers are placed over the filled cell whenever there is likelihood that the contents might be harmed or contaminated. When the cell is handled with the cover on, the cover 17 is sealed all around the edge to the cell top angle 14 with any suitable adhesively applied tape such as the tape used in sealing the enclosures of spaces to be fumigated. To eliminate congestion of unnecessary drawing detail the sealing tape is not shown in the figures.

When grain is handled and stored during the harvest season, the cells of grain are usually not covered until brought to the storage yard and placed in position. Then the cell is covered with a cover 17 before the next upper cell is placed on the cover effectively to hold the cover tightly on the cell. In this case the top cells of the block have their covers held on by sealing or other desired method.

Rotatably secured to each of the cells as shown for cell 12 in Figs. 2 and 3 is a cover strap 18 held by shouldered bolt 19 as shown. Equally distant from bolt 19, strap 18 has formed therethrough two countersunk holes 20 and 21 either of which may be placed in register with hole 22 formed in the front wall of cell 12. Secured between strap 18 and the face of cell 12, in hole 20 as shown, is a grommet or thick edged rubber diaphragm 23 which will hermetically seal hole 22 when strap 18 is rotated to register holes 20 and 22. Secured between strap 18 and the face of cell 12 in hole 21 as shown is a disk of fine metal screen 24 of mesh small enough to prevent dirt and vermin from entering hole 22 when strap 18 is rotated to register holes 20 and 21. However, the mesh of screen 24 is such as to allow ventilation of the interior of the cell.

In Fig. 4 is shown the novel and useful device for fumigation of bulk grain in accordance with the teaching of this invention. A commercial container in which the fumigation material methyl bromide is purchased is shown at 25 in a stirrup 26 formed with a threaded hole at 27 to receive a threaded nipple 28. The closure of container 25 at its neck 29 is so formed with a displacement valve that when nipple 28 is screwed tightly into neck 29 through strap 27 the interior of container 25 is opened to the interior of nipple 28. Thus in renewing the supply of methyl bromide by replacing the container 25, the nipple 28 is left connected to inlet 37 of three way valve 30 and stirrup 26 is unscrewed from nipple 28 to release container 25. Then a new container 25 is placed in stirrup 26 and stirrup 26 is screwed into nipple 28 sufficiently far to open the interior of container 25 to the interior of nipple 28.

Transparent measuring chamber 31 graduated as shown at 32 and sealed into fitting 33 is connected to the common opening 38 of three way valve 30 by nipple 34. Hollow needle 35 having discharge openings 36 is threaded into opening 39 of valve 30. When handle 40 of valve 30 is pointed directly upward a path is opened from the methyl bromide storage chamber 25 to the measuring chamber 32 and when handle 40 is pointed directly in line with needle 35 the needle 35 is connected directly with chamber 32. It should be remembered that methyl bromide is a liquid at usual atmospheric pressures and temperature near the freezing temperature of water but at lower pressures or higher temperatures the bromide will be in its gas phase. Then at say 50 degrees Fahrenheit temperature and 29 to 30 inches of Hg atmospheric pressure, if the fumigation device is held by stirrup handle 41 in the upright position shown and valve handle 40 is pointed towards container

25, the vapor phase of the bromide will aid gravity in pressing the bromide in its liquid phase into measuring chamber 32 which can be supplied with the desired amount of liquid for one fumigation "dose" as indicated on the graduation scale 32. When the proper charge has been measured, the handle 40 can be moved to its intermediate position shown or if the pointed end of the needle 35 with its opening 36 is in the space to be fumigated the valve handle 40 can be moved to its position of alignment with needle 35 and the bromide discharged from chamber 31 through needle 35 and out of openings 36. The bromide will discharge for when valve stem 40 is moved to connect chamber 31 with needle 35 the pressure in chamber 31 is immediately reduced to atmosphere, the bromide in chamber 31 in its liquid phase immediately changes to its vapor phase and expands so greatly in volume as to be almost entirely discharged through needle openings 36.

When it is desired to fumigate the grain in one of the cells or bulk storage containers the operator rotates the strap 18 to register diaphragm 23 with hole 22 and then shoves the needle 35 through the diaphragm 23. A dose of fumigant is then measured into chamber 31 by turning valve handle 40 upward towards container 25. When the desired amount of fumigant is seen in chamber 31 valve handle 40 is pointed towards needle 35 and the fumigant in chamber 31 volatilizes and discharges out holes 36 of needle 35 into the cell. The needle 35 is withdrawn from the diaphragm 23 which seals itself within the requirements of the fumigation process.

It is thus seen that this invention provides for cereal grains and grass seeds, bulk storage in multiples of standardized lots the lots being contained in easily handled, transported, stored and fumigated cells of a unique utility and provided with means for ventilating or hermetically sealing the cells.

Having recited some of the objects of the invention disclosed and described preferred forms of the structures involved in the practice of the invention and described their operation, we claim:

1. A bulk storage system including the combination of a hollow open topped box for the storage of seed grain and means for fumigating the seed grain while stored in said box, said box being formed with an inspection hole on one side thereof near said top and a pair of parallel laterally spaced skids for supporting said box with its bottom above a support for said skids, said combination including means adapted selectively to screen said hole to allow said box to breathe while excluding vermin from said box and to cover said hole with a self closing puncturable diaphragm, and cover means removably sealable over the top of said box, said fumigating means including a hollow needle adapted to be pressure entered into said box through said diaphragm, said needle having a blunt open end a closed pointed end and an outlet hole through a side wall thereof near its pointed end, together with a storage container for liquid fumigant, a dose measuring container below said storage container for liquid fumigant, conduit means connecting the lower end of said storage container with the upper end of said dose container, said conduit including means for alternately filling said dose measuring container from said storage container and emptying said dose measuring container of fluid fumigant through said needle into said box, said storage container including therewith a carrying handle for maintaining said storage container at a higher elevation than said dose container.

2. For use in a bulk storage system for seed grain, a substantially cubical open topped box having slightly shorter sides at one end of the box than at the other whereby the box is in the form of a frustum of a pyramid having a rectangular base, the top of said box being finished on the outside with a flat collar parallel to the base of the box, the under side of the box including a pair of laterally spaced hollow open ended skids adapted to receive therein the forks of a fork lift truck and one

flat side of said box near its top edge being formed with an inspection fumigation and breather hole therethrough and said box including a removable puncturable self-sealing diaphragm cover for said hole.
